UNITED STATES PATENT OFFICE

FENTON WRIGHT, OF KANSAS CITY, MISSOURI

SHIRT FASTENER

Application filed August 7, 1929. Serial No. 383,992.

The present invention is directed to improvements in shirt fasteners.

The primary object of the invention is to provide an article of this character so constructed that the front of a shirt can be firmly fastened without the necessity of using buttons or other similar securing devices.

Another object of the invention is to provide a device of this character so constructed that the fastening devices will add to the attractive appearance of the shirt, the construction being such that the shirt front can be easily and quickly opened or fastened, as desired.

Another object of the invention is to provide a device of this kind which is also applicable to the cuffs of shirts.

With these and other objects in view, this invention resides in the novel features of construction, formation, combination and arrangement of parts to be hereinafter more fully described, claimed, and illustrated in the accompanying drawing, in which:

Figure 1 is a front view of the shirt showing the same equipped with the fasteners.

Figure 2 is a sectional view on the line 2—2 of Figure 1.

Figure 3 is a sectional view on the line 3—3 of Figure 1, taken through a cuff of a shirt.

Figure 4 is a fragmentary outside view of a portion of a shirt body showing one of the strips secured thereto.

Figure 5 is a sectional view showing a modified form of fastener.

Referring to the drawing, 1 designates the body of a shirt, the same being provided with the usual neck band 2 and button closure 3'. The body 1 is of coat-like form and has its front portions provided with hems 3 and 4, the latter having slits 5 formed therein, said slits being vertically spaced, it being obvious that the number of slits may vary according to the manner in which the shirt is to be fastened. The body portion carrying the hem 4 is provided with slits 6 and 7, the purpose of which will later appear. Having one of their ends secured to the body portion carrying the hem 3, are strips 8 which are preferably two-ply and are reinforced trans-

versely by lines of stitching 9, as most clearly shown in Figure 4 of the drawing. The strips when in their fastened positions are folded at a point between the lines of stitching 9, which not only reinforces the strips 55 at these points but serves as a guide in order that the strips may be folded at the proper points. The strips are of such width that they can be passed through the slits 5, 6 and 7 with comparative ease. Reinforcing 60 patches 10 are attached to the body portion bearing the hem 4 and are provided with slits 11 and 12, which coincide, respectively, with the slots 6 and 7.

It will be observed upon reference to Figure 2, that the strips 8, when fastening the front of the shirt, are passed through the slits 5 and thence through the slits 6 and 11, and are folded between the rows of stitching 9. The strips are then passed through 70 the slits 7 and 12 and slits 5, so that the terminals of said strips will be exposed. The strips are starched slightly in order that they may be more conveniently guided into the respective slits during fastening of the shirt. 75 It will be noted that when the shirt front is closed that the hems 3 and 4 will be maintained in overlapped relation and will be held against distortion or buckling.

In Figure 3 is illustrated the meeting 80 edges 13 and 14 of a cuff and from the edge 13 extends or leads the strip 15, while the other edge is provided with slits 16, 17 and 18, through which the strip 15 is passed in a manner similar to the manner in which the strips 8 are passed through the slits of the shirt.

Tabs 19 may be fixed interiorly of the shirt body 1 so as to cover the slits 6 and 11, so that when strain is applied to the shirt 90 front tending to cause the slits to gap, the tabs will conceal the underwear of the wearer.

It will thus be seen that a shirt fastener has been provided which is not only effective for securing the shirt but will add to the ornamental appearance of the shirt.

In Figure 5 the strip is provided with relatively stiff independent sections of webbing 20 which are engaged between the plies 100

of the strip and serve to stiffen the same so that, when the strip is not starched it may bend freely between the stitches 9-9.

While the fastener is illustrated for use in connection with a dress shirt it is not necessarily limited to such use since it can be used in connection with various kinds of wearing apparel.

What is claimed is:

- 10 1. A shirt having its body provided with separable portions, one portion having inner and outer slits and intermediate slits, strips having one of their ends secured to the other portion, said strips being passable first 15 through the inner slits and then through the outer slits, said strips being foldable in the outer slits and then passable through the intermediate slits and the inner slits.
2. A garment having separable portions, 20 one portion having slits therein, strips secured to the other portion consisting of two plies, reinforcing elements between the plies having their adjacent ends spaced, said strips being passable through the slits and bendable 25 between the ends of said elements.

In testimony whereof I affix my signature.
FENTON WRIGHT. [L.S.]
